UNITED STATES PATENT OFFICE.

GUY MILBURN, OF BALTIMORE, MARYLAND, ASSIGNOR OF ONE-HALF TO WILLARD G. MILBURN, OF BALTIMORE, MARYLAND.

AUTOMATIC SIGNALING DEVICE.

No. 885,168.

Specification of Letters Patent. Patented April 21, 1908.

Application filed May 11, 1906. Serial No. 316,380.

To all whom it may concern:

Be it known that I, GUY MILBURN, a citizen of the United States, residing at Baltimore city, State of Maryland, have invented 5 certain new and useful Improvements in Automatic Signaling Devices, of which the following is a specification.

This invention relates to train signaling mechanism, and has for its principal object 10 to provide a novel block system in which signals are automatically displayed in the cab of the locomotive or at any other suitable point in the train, with a view of avoiding collisions.

15 A further object of the invention is to provide for the automatic display of three different sets of signals whenever a block is occupied by a train; first, a caution signal is given, and next a danger signal is displayed 20 within the cab, and the engineer's attention is called to these signals by both visible and audible alarms, the signals being arranged to advise the engineer approaching of the presence of a train in a block beyond that in 25 which he is about to enter.

A still further object of the invention is to provide for the changing of certain of the signals when a second train passes into the block adjacent to the one already occupied, 30 thus notifying the engineer. When no signals are displayed the fact indicates to the engineer that the track is clear.

With these and other objects in view, as will more fully hereinafter appear, the invention 35 consists in certain novel features of construction and arrangement of parts, herein-after fully described, illustrated in the accompanying drawings, and particularly pointed out in the appended claims, it being 40 understood that various changes in the form, proportions, size and minor details of the structure may be made without departing from the spirit or sacrificing any of the advantages of the invention.

45 In the accompanying drawings:—Figure 1 is a diagram illustrating a portion of a system arranged and constructed in accordance with the invention, showing an entire block. Fig. 2 is a similar view illustrating the wiring 50 of a block indicated as No. 2. Fig. 3 is a similar view illustrating the wiring of a block indicated as No. 3. Fig. 4 is a view in the nature of a diagram illustrating the mechanism arranged within the cab of the 55 engine. Fig. 5 is a detail view of one of the

multiple armatures composed of several laminæ for the purpose of controlling the number of circuits.

Similar numerals of reference are employed to indicate corresponding parts 60 throughout the several figures of the drawing.

The drawings illustrate the application of the invention to a single track railway, and A, A¹, A², A³, A⁴ and A⁵ indicate the rails of 65 block No. 1, and A⁶ the rail connecting block No. 1 with block No. 2.

A⁷, A⁸, A⁹ and A¹⁰ indicate the rails of 70 block No. 2, and A¹¹ the rail connecting block No. 2 with block 3.

A¹², A¹³, A¹⁴ and A¹⁵ indicate the rails of 75 block 3, and the several blocks are insulated from each other as indicated at 3^a, 3ⁱ and 3ⁿ.

The several blocks are similarly wired, and three of such blocks are shown in order 75 that the circuits connecting them for the transmission of signals from block to block may be more readily traced.

Arranged within block 1 are three circuit controlling electro-magnets, t¹, t², t³. In 80 block 2 are three similar electro-magnets t⁴, t⁵, t⁶, and in block 3 are three similar magnets t⁷, t⁸ and t⁹. These magnets are arranged in circuit with suitable batteries indicated at 10, 11 and 12, in block 1; 13, 14 85 and 15 in block 2, and 16, 17 and 18 in block 3, the wiring in each case being the same.

Referring first to Fig. 2, the circuit may be traced from the battery 15 over rail A⁹ and conductor 94 to electro-magnet t⁵ and from 90 thence through conductor 95 to the rail A¹⁰, back to battery 15. If an engine arrives in this section of the track, the battery 15 will be short circuited and the electro-magnet t⁵ will be deenergized.

95 From one pole of the battery 14 the current flows to rail A⁷, over wire 96 to electro-magnet t⁴, back over wire 97 to rail A⁸, back to battery 14, and if an engine arrives on this section of track, the battery 14 will be 100 short circuited, and the electro-magnet t⁴ will be deenergized.

One pole of the battery 13 is connected to rail A⁶ and thence by wire 98 to electro-magnet t³ to block No. 1, back over wire 99 105 to rail A⁵, thence to wire 99^a of the armature L of the electro-magnet t⁵ over said armature to its contact plate n, wire 99^b, armature L of electro-magnet t⁴ to contact plate n, conductor 99^c, back to the negative pole 110

of the battery 13. The similar circuits of the remaining blocks are wired in exactly the same manner.

When any one of the electro-magnets is deenergized, its corresponding armature will be drawn away from the pole of the magnet by a suitable spring, this being indicated at 5 S^1 , S^2 , S^4 in block 1; S^5 , S^6 , S^8 in block 2, and S^9 , S^{10} and S^{12} in block 3. In block 1 there 10 are, also, arranged two electro-magnets c , d , and in block 2 are two corresponding magnets c' , d' , and in block 2 two magnets c^2 and d^2 , and associated with these are multiple armatures designated generally by the reference 15 letter L, the armatures being pulled away from the poles of the magnet when the latter are deenergized by means of suitable springs S^{13} — S^{18} .

The rail sections A and A^3 are connected 20 electrically by a wire 70 to contact plate n' of magnet d , lamina L' of the armature of the same magnet, wire 71, contact plate n' of magnet c , lamina L' of the armature of the same magnet, wire 72, back to the track section A^3 .

The rail sections A^2 and A^5 are electrically connected by means of a wire 73 leading to contact plate n of magnet c , lamina L of the armature of the same magnet, wire 74 and 30 wire 99^b to track section A^5 , and there are similar circuits in the remaining blocks.

The electro-magnet d is connected in a circuit which may be traced from a battery 7 through wire 99^d to the electro-magnet, 35 thence through wire 99^e to the lamina L' of the armature of magnet t^3 to contact plate n' , over wire 99^f, back to the negative pole of the battery 7, and similar circuits may be traced in any of the remaining blocks.

40 In each of the blocks there is, also, arranged an electro-magnet for controlling a semaphore signal arranged at the side of the track, thus, for instance, in block 1 there is an electro-magnet r having an armature L arranged to engage a contact n and close a circuit over a wire 120 to a battery 121 and solenoid 122 which operates the semaphore R, and back over wire 123 to the armature L. In similar manner an electro-magnet h' in 45 block No. 2 controls the operating circuit of a semaphore R' and in block 3 an electro-magnet h^2 controls the circuit of a semaphore R². The several armatures of these electro-magnets are shown as acted upon by 55 springs S^3 , S^7 and S^{11} , respectively.

The electro-magnet r is included in a circuit which may be traced from battery 1 to the electro-magnet, wire 99^e, electro-magnet c^6 , wire 99^b, to rail A^5 , over rail A^5 to the opposite end, thence by wire 99ⁱ to contact plate n^2 of electro-magnet d' , lamina L' of the armature of said electro-magnet, over wire 100 to the opposite pole of the battery 1. When this circuit is closed through the battery, the electro-magnet r is energized, and

its armature L is held from movement, so that the semaphore R will not be moved to display position. In similar manner the electro-magnets h' and h^2 are connected in circuit with batteries 2 and 3, respectively, 70 and these control the semaphores R' and R².

The magnets which control the semaphores R, R' and R² are energized when it is desired to display an outside caution signal, 75 and in addition to these caution signals, there are, also, danger signals M, M' and M² located adjacent to the ends of the blocks and these are under the control of the electro-magnets t^3 , t^6 and t^9 . In tracing the circuit 80 of the danger signal, it will be seen that a wire 130 runs from a battery 131 to the contact n of the electro-magnet t^3 , thence through the lamina L of the armature of the same magnet, wire 131, to a solenoid 132, 85 and thence back to the battery. So long as the circuit of this solenoid is energized by the engagement of the armature with the contact n the semaphore will be held from movement, but when the circuit is opened by the deenergizing of the electro-magnet t^3 , the semaphore will be allowed to move to display position, and show a danger signal, warning 90 the engineer of the presence of a train in the block ahead, while the caution signal warns him of the presence of a train in the second block ahead.

In the several blocks are arranged additional batteries, the battery 4 in block 1, the battery 5 in block 2, and the battery 6 in 100 block 3. The circuits of these batteries are normally open, but when the electro-magnet c is deenergized, and the spring S^{14} moves its armature away from the pole of the magnet, the lamina L of the armature engages 105 the contact m . This connects the positive pole of the battery 4 with the rail section A^5 , the circuit being traced from positive pole of the battery through wire 85, contact plate n , of electro-magnet d , lamina L of the armature of the same magnet, contact m , lamina L of the electro-magnet c , wire 74, and wire 99^b to the rail section A^5 . When this is done, the battery is ready to operate the mechanism on the engine for displaying a 110 caution signal, and it is to be here understood that the battery 4 is thus connected by a train two blocks ahead, that is to say, a train in one block will so operate the connections, that the battery 4 in the second 115 block behind it will be ready to operate on the mechanism in the engine to display a caution signal, but in the block immediately behind that in which the train is located, the battery will not be so located, and if another 120 train arrives in this block, the signals of that train will be sent to danger position. The other pole of battery 4 connects with rail A^2 through wire 73. The circuit is completed 125 from A^5 to A^2 through the train circuits, in a 130

manner more definitely to be described hereinafter.

Turning now to Fig. 4, which illustrates diagrammatically the arrangement of the cab connections and signals, 45 and 32 designate two semaphores pivoted at 47 and 34, respectively, and provided with lenses 46 and 33 which are movable over lamps 51 and 50, respectively, one carrying a green lens and the other a red lens. In the cab are, also, arranged two electric bells 26 and 27 which form the audible alarm.

As shown in Fig. 4, the parts are in normal position, that is, that no signal is displayed, and connections made between the cab and the traffic rails by means of two wires 76 and 77, the wire 76 being connected to one of the axles of the engine, and the wire 77 being connected to one of the axles of the locomotive tender or baggage car, this connection being shown in Fig. 1. In wire 77 is arranged a battery 19 which is connected to an electro-magnet 75, thence to contact plate 56, over lamina 60 of the armature of the magnet over conductor 76 to the engine, and thence back over the rails to the wheels of the tender of the same train, and back over conductor 77 to the opposite pole of the battery. So long as the wheels of the engine tender are in electrical contact through the rails, the electro-magnet 75 is energized, and if they are insulated from each other as by straddling, the insulating points 3, 3^a, 3^b, 3^c, etc., the circuit will be broken, and the electro-magnet 75 will be deenergized. The engine further carries a battery 24 connected to contact plate 48, and the current thence flows over wire 90 to the bells 26 and 27 which are connected in multiple to wire 91, electro-magnet 23, and back to battery 24. This current is insufficient to ring the bells, but is sent through them, so that if an open circuit should occur in the wires which lead to the bells, the electro-magnet 23 would be deenergized allowing its armature 25 to be drawn away from contact plate 24^x by tension spring 80, thus opening one of the circuits of a battery 22, and deenergizing the solenoid 30. When this occurs the semaphore arm 32 moves upward by reason of the weight on the lens side of the pivot, and displays a danger signal.

The circuit from the battery 22 may be traced to armature 25, contact plate 24^x, solenoid magnet 30, wire 81, contact plate 59, lamina 69, wire 82, back to the opposite pole of the battery. Current also flows from battery 22 over conductor 83, semaphore arm 45, contact plate 40, solenoid magnet 42, wire 84, wire 81, contact plate 59, lamina 69, and wire 82 back to battery 22.

In the engine cab there is also arranged a dash pot 54 in which is a movable piston 52 carrying a contact plate 52' which is engaged at one end by the lamina 60 of the armature

of electro-magnet 75, this armature being pivoted at the point 69. An insulating block or blocks 55 is interposed between the lamina 60, and the contact plate 52', so that no current can pass, and if the electro-magnet 75 is deenergized and the lamina 60 is allowed to move away from the plate 52', the piston 52 of the dash pot will move inward, as, for instance, under the action of contractile spring 200, and contact plate 52' will engage the contact 53, closing a circuit of which mention will be hereinafter made. In the engine cab there are, also, arranged two electro-magnets 64 and 65, which control a pivotally mounted armature 66, these being arranged in circuits which are under the control of the electro-magnet 75.

If a train is at any point in block 3, say, for instance, on the rails A¹⁰ and A¹¹, the electro-magnet *t*⁶ will be deenergized, allowing its armature to be drawn away from the contact plates *n* and *n'*, thus displaying the outside danger semaphore arm M', and also breaking the circuit to battery 8, thereby deenergizing electro-magnet *d'*, and allowing its armature to be drawn away from its contact plate, thereby breaking electrical connection between the rails A⁵ and A⁶, and also breaking the circuit of the battery 1 which results in deenergizing the electro-magnet *r*, and permitting movement of the caution signal R to display position, so that in block 1 a caution signal is displayed, and in block No. 2 a danger signal is displayed. As the electro-magnet *c* of block No. 1 is also deenergized the lamina L of the armature of this magnet will engage the contact *m*, and the positive pole of the battery 4 will be electrically connected with the rail section A⁵ through the wire 85, the armature of electro-magnet *d*, contact plate *m*, lamina L of the armature of electro-magnet *c*, wires 74 and 99^b to the rail A⁶. If another train is then in block 1, straddling the insulating joints 3 and 3^a, as shown in Fig. 1, the circuit of the battery 19 of the engine will be broken, and magnet 75 will be deenergized, thereby breaking the circuit of the battery 22, and deenergizing the solenoids 30 and 42, allowing both semaphore arms to rise, by reason of the weights on the lens side of their pivots 34 and 47. This allows the lamina 60 of the armature of electro-magnet 75 to move into engagement with contact plate 57 and the lamina 58 of the armature to move into engagement with the contact plate 62 while the dash pot piston 52 is released, and the contact plate 52' moves into engagement with the contact plate 53.

As the engine travels along until the engine wheels pass beyond the insulating sections 3^b and 3^c, the positive pole of the battery 4 is placed in inter-communication through the rail A⁵ with the engine wheels and wire 76, the current running to lamina 60

of the armature of the electro-magnet 75 to contact plate 57, electro-magnet 64, conductors 86 and 77 to the axle of the tender T, over said axle and its wheels to the rail section A², conductor 73 to the opposite pole of the battery 4. This energizes the electro-magnet 64 of the engine, causing it to attract the armature 68 which is hinged at 66, and thus bring said armature into engagement with the contact plate 63, thereby completing the circuit of a battery 20, the circuit being traced from the battery to a wire 140, contact plate 63, armature 68, electro-magnet 65, wire 141, lamina 58, contact 62, wire 143, solenoid 38, wire 144, back to battery 20 thus energizing the electro-magnet 38, and drawing down the semaphore danger signal 32, leaving only the green or caution semaphore arm to remain up as a caution signal. Considering the advanced train still remaining in block 3, and the engine of block 1 traveling toward block 2 with the caution signal displayed, as soon as the contacts of the engine and tender straddle the insulating joints 3^e and 3^f, metallic connection between the rails A⁶ and A⁸ being broken, the circuit of the battery 19 on the engine will again be broken, allowing the red semaphore arm to rise, both arms remaining up as a danger signal, and when the engine in traveling forward straddles the insulated joint 3^e and 3^b, the battery 5 will not send a circuit through the electro-magnet 64 of the engine, as did the battery 4, because the armature of the electro-magnet 64 will not be released, for in order to accomplish this the advanced train must be two blocks ahead, whereas in this case it is only a single block ahead.

When the armature of the electro-magnet 75 is released and the piston 52 of the dash pot 54 is allowed to move until the contact plate 52' strikes the contact 53, current will pass from the battery 19 through the magnet 75 over conductor 88 to contact 53, contact 52', piston 52, the metallic dash pot 54, conductor 87, a conductor 76, over the wheels of the engine, and over the rails, (the engine and tender having passed the insulated joints), to wheels and axles of the tender, and over conductor 77 back to the opposite side of the battery, thereby energizing the electro-magnet 75 which will attract its armature and break the circuit of the battery 20, thereby deenergizing the electro-magnet 65 and allowing its armature to assume the normal position shown in Fig. 4. This deenergizes the solenoid 38. When the armature of the electro-magnet 75 is attracted, current again flows from the battery 22 through the solenoid 38, holding the semaphore arm 42 down as soon as the circuit of the battery 20 is broken. When the engineer sees the caution signal, he lowers the semaphore arm 45, which establishes a circuit from the battery 22, through the solenoid 42, as previously

described, which holds the green semaphore arm down.

The engineer's attention is called by the bells 26 and 27 which ring simultaneously with the rise of the semaphore arm. When the green semaphore arm rises, it makes contact with the plate 48, allowing current to flow from the battery 22 through the semaphore arm, contact plate 48, conductor 90, through bells 26 and 27 and conductor 91 back to battery 22. When the green arm rises, the lamina 39 comes into engagement with the contact 49. Current then flows from battery 21 over conductor 92 to contact 49, conductor 93 to the lamina 50 and 51 which are in multiple, back to the battery 21, thus lighting the lamps.

It will be seen that any engine traveling over the road will so set the circuits that a following engine two blocks in the rear will have a caution signal displayed, and the bells will be rung, and the lamps ignited, and at the end of the block an outside semaphore caution signal will, also, be displayed. If the following engine enters the block immediately behind the first train, the danger signals will be set on the following train, and the outside danger semaphore signal will, also, be set, and this operation will continue throughout the length of the road.

I claim:—

1. A signaling system in which the track sections are divided into insulated blocks, and electro-magnetically operated means under the control of an engine in one block for effecting the display of a danger signal in the next adjacent block, and a caution signal in the second block, a signal on each engine, the last said signal being continuously connected with the block conductors, and a source of energy normally disconnected from the block conductors and arranged to be connected thereto by an engine in a block other than that through which the signal is to be operated.

2. A signaling system divided into insulated blocks, caution and danger semaphores in each block, electro magnets normally holding the semaphores in non-signaling positions, and circuits in which said electro-magnets are disposed, the circuits being controlled by an engine to effect the display of a danger signal in the block next adjacent to that in which the engine is located, and a caution signal in the second block, a signal means on each engine, said signal means being continuously connected with the block conductors and a source of energy normally disconnected from the block conductors and arranged to be connected thereto by an engine in a block other than that through which the signal is operated.

3. In train signaling rails divided into insulated blocks, electro-magnets arranged in each block and under the control of trains

- which have passed beyond the block in which they are located, a source of energy arranged in each block and arranged to be connected to one of the block conductors, a signal means on each engine, said signal means being continuously connected with the block conductors, and a source of energy normally disconnected from the block conductor and arranged to be connected thereto by an engine in a block other than by which the signal is operated. 5
4. A railway signaling system divided into blocks, a signal or alarm means on each engine, said signal or alarm means being continuously connected with the block conductors, and a source of energy normally disconnected from the block conductors and arranged to be connected thereto, by an engine or train in a block other than that through which the signal is to be operated. 10
5. In railway signaling systems, rails divided into insulated blocks, a source of energy arranged in each block and normally disconnected from the rails, means under the control of an engine through a distant block for connecting the source of energy to the rail, and a signaling circuit on the train arranged to be energized from such source of energy. 15
30. 6. In a railway signaling system, rails divided into insulated blocks, a source of energy arranged in each block and normally disconnected from the rails, an electro-magnet in each block for controlling the connection of the source of energy to the rails, an electro-magnetic circuit, the terminals of which are under the control of a train in a distant block, a signaling means carried by the train and arranged to be electrically connected to the source of energy as the train travels through the block. 20
7. In a railway signaling system, a track divided into blocks, each block being further divided into a series of insulated sections, an electric battery arranged in each section, electro-magnets connected to the several electric batteries, and signaling devices arranged in the several blocks and having circuits under the control of said electro-magnets. 25
50. 8. A railway signaling system in which the rails are divided into insulated blocks, a battery arranged in each block and normally disconnected from the rails, an energized circuit arranged on each train, signaling devices under the control of the circuits, the signaling devices being movable to operative position during the passage of the train over insulated sections of the rail, and means operable by the block battery for restoring one of the signals and leaving the other in display position. 30
9. In a railway signaling system, rails divided into blocks, a separate battery for each block, a plurality of signaling devices on each train, a controlling circuit for the signaling devices, the terminals of said circuit being connected to the rails at distant points in the length of the train, whereby the circuit may be opened as the train passes over an insulated portion of the track, and means for connecting the block battery to the train circuit to complete the same and effect movement of one of the signals. 35
10. In train signaling systems, rails arranged in blocks, a separate battery for each block, the battery being normally disconnected from the rails, means under the control of a train in a distant block for connecting the battery to the rails, a plurality of signaling devices on each train, a controlling circuit therefor, the terminals of such circuit being connected through the running gear of the train to rails at distant points in the length of the train, and means operable on connection with the block battery for effecting movement of one of said signals. 40
11. In train signaling systems, a pair of semaphores arranged on each train, solenoids controlling the movement of the semaphores, a pair of bells, and a pair of electric lamps, the circuits of which are under the control of one of said semaphores, battery connections leading through the solenoids, track contacts forming terminals to a controlling circuit on the train, and a series of electro-magnets and armatures and controlled by said circuit, and serving to effect movement of the semaphore arms to idle and display position in accordance with the nearness of approach of the train to the danger point. 45

In testimony whereof I affix my signature in presence of two witnesses.

GUY MILBURN.
